PHOTOGRAPHIC COLOR RECORDING
MACHINE

James W. Bryce, deceased, late of Glen Ridge, N. J., by Elizabeth Snow Bryce, Glen Ridge, N. J., and The National Newark and Essex Banking Company of Newark, Newark, N. J., executors, and Robert T. Blakely, Amityville, N. Y., assignors to International Business Machines Corporation, New York, N. Y., a corporation of New York

Application August 13, 1949, Serial No. 110,197

10 Claims. (Cl. 95—4.5)

1

This invention relates to an improved record controlled photographic recording machine, and more particularly to a machine adapted to the photographic recording of characters in one or more colors.

The type of machine to which this improvement relates is shown in U. S. Patent No. 2,346,251 to James W. Bryce. The machine of the Bryce patent achieved photographic recording under control of perforated record cards by selectively flashing gaseous discharge tubes in timed relation with the rotation of a character drum which is transilluminated by the flashing tube, thereby exposing a photographic film on which the record is made.

It is a general object of this invention to provide a machine of the type indicated to record in more than one color under selection of record sources such as perforated record cards from which are derived the data to be recorded.

It is a further object of the invention to provide a machine for recording photographically in more than one color on a single photographic record medium.

It is a further object of the invention to provide for the simultaneous recording in selected columns of a record medium, and particularly to provide such recording in different colors.

It is another object of the invention to provide individual column control of color recording in recording operations using a photographic recording medium.

A still further object of the invention is to provide auxiliary color control mechanism cooperating with flash tubes during the recording operation so that one or more columns of data may be recorded simultaneously in different colors.

It is still a further object of the invention to provide a plurality of differently colored recording devices which may be selectively brought into operation under control of the record source.

It is also an object of the invention to provide means for presetting a color recording device which will result in the color recording of data in preselected columns of the recording film.

The objects of the invention are attained by providing a machine having a card handling and sensing section through which perforated record cards are passed, and from which a recording section is controlled. Basically the recording section includes a camera unit having suitable lens structure through which a color sensitive photographic film may be exposed as it is passed from a feed spool to a take-up spool in synchronization with the passage of cards through the card handling and sensing section. The record-

2

ing section includes a rotatable character drum which is opaque but for columns of characters formed therein through which gaseous discharge lamps within the drum are adapted to illuminate the photographic film, the rotatable character drum being rotated in synchronism with the passage of a card through the sensing section so that as a perforation is sensed in the card a corresponding drum character is positioned at a transilluminating slot in front of the gaseous discharge lamp. Each drum has a separate discharge lamp related to each character column in the periphery of the drum, and the lamps are selectively fired under the control of card perforations.

15 The color recording herein to be described may be achieved in a plurality of different ways. In one form of the invention color screens are provided on movable strips which correspond in position and number to the character columns in the 20 wall of the rotating character drum. The color screens of the respective strips may be brought into alignment with the character of the drum at the exposure position under the selective influence of record cards being processed. When a 25 color screen is positioned at the exposure zone of any given column, the recording on the color sensitive photographic film will be in a corresponding color.

In a modified form of the invention a plurality of character drums are provided, specifically two 30 such drums, and the discharge lamps of the respective drums are selected to produce under their natural illuminating power a desired color in the record film. Thus, in the example that is to be described more specifically hereinafter, it is proposed to provide neon lamps in one of the character drums, thereby producing on the record film a red recording, and mercury vapor lamps in the second drum, the rays of the mercury vapor lamps being effective to produce a bluish white recording 35 on the recording film. In the modified form of the invention the drums and their associated lamps are also under control of record cards being sensed in the record card handling and sensing section, and the drums and their illuminating 40 lamps are consequently automatically and selectively operated to produce the desired color recording under record card control.

The manner in which the invention is practiced will appear more particularly as the description 50 thereof proceeds with reference to the drawings forming a part of this application and in which drawings:

Fig. 1 is a perspective view of the machine in which the invention is embodied;
55 Fig. 2 is a cross-sectional view through a flash

tube unit, a character drum and color screens constituting the photographic medium exposure mechanism of one form of the invention;

Fig. 3 is an elevational view of the drive mechanism connected with the instrumentalities shown in Fig. 2;

Fig. 4 is a fragmentary view of a plurality of color screens used in connection with a rotating character drum and tube flash unit, the view being taken on line 4—4 of Fig. 2;

Fig. 5 is a cross-sectional view on line 5—5 of Fig. 3;

Fig. 6 is a cross-sectional view on line 6—6 of Fig. 1, showing a modified form of the invention;

Fig. 7 is a cross-sectional view on line 7—7 of Fig. 1 showing the modified form of the invention;

Fig. 8 is a control circuit diagram;

Fig. 9 is a control circuit for rendering operative movable color screens as taught in one form of the invention;

Fig. 10 is a diagram of a circuit for rendering operative the modified form of the invention; and

Fig. 11 is a timing diagram.

Referring now particularly to Fig. 1, the machine in general comprises a record handling and record reading section 10 and a recording section or unit 12. Suitable shafting connects the recording section and the record handling and analyzing section whereby the operative devices of the respective sections may be driven by a motor 14. The motor 14 through conventional worm gears and shafts is adapted to drive a main drive shaft 16. The drive shaft 16 directly drives parts in the recording section, as will be subsequently described. It also drives a plurality of so-called C cams, specifically herein referred to as the cams C-1 through C-4 which are keyed to the shaft. Attached to the shaft 16 is a gear 18 which drives a gear 20. Fixed to the gear 20 is a one-revolution clutch mechanism 22 which is freely rotatable on a shaft 24. A clutch dog 26 is pivoted to an arm 28 which is fixed to the shaft 24. The clutch dog 26 is adapted to be tripped into engagement with a notch in the clutch plate 22 upon energization of a card feed clutch magnet 30. Driven by and secured to the shaft 24 are two distributing commutators CD-1 and CD-2. Also attached for rotation with the shaft 24 are cams CF-1 through CF-11A. Gearing 32 transmits drive from the shaft 24 to a main drive shaft 34 of the card handling and sensing section. The card handling and sensing section is of customary construction, and it includes a supply hopper 36 and a stacker or discharge hopper 38. The card handling and sensing unit is also provided with driven card feed rolls which are driven by helical gearing 40. Within the card sensing section is a conventional card picker which is adapted to pick cards one at a time from the bottom of a card stack in the hopper 36 and advance such cards into the bite of feed rolls, whereafter the cards pass between sets of contact rollers 42 and 44 and related sensing brushes B-1 and B-2, respectively, for detecting perforations therein. The cards passing through the card sensing section also come into contact with card levers 46 and 48. After the cards have been analyzed in the card sensing section, they are discharged into the receiving hopper 38. The contact rolls 42 and 44, their related sensing

brushes B-1 and B-2, respectively, and the card levers 46 and 48 are shown in Fig. 8 of the drawings, and their particular disposition in the card sensing section is disclosed in Fig. 7 of the Bryce patent noted above.

Recording unit 12 includes a suitable base 50 which has attached thereto a pair of side plates 52 and 54, and by particular reference to Fig. 5, it may be seen that suitable bearings 13 in the side plate 52 afford a journal for the end of the drive shaft 16. The drive shaft 16 through suitable gearing 56 is adapted to drive a drum driving gear 58. The drum drive gear 58 is suitably fixed to one of the end hubs 15 60 of a character drum 62. The hubs 60 are rotatably mounted in bearings 64 supported in the side plates 52 and 54. Attached to the hub sections 60 of the character drums 62 are annular members 66 which support the character drum 62. The drive gear which drives the drum is preferably proportioned so that the drum 62 will make one complete revolution during three machine cycles, that is to say, if three cards in succession pass the sensing brushes during the transit of these three cards, there will be one complete revolution of the drum 62. The drum is rendered opaque except at the character displaying portion thereof where the drum is transparent or translucent.

Disposed within the drum are a plurality of gaseous discharge tubes such as neon or mercury vapor tubes 68. Normally these tubes are not energized. When it is desired to record, a source of potential is momentarily applied to the gaseous discharge tube at the instant the desired character in the wall of the drum is in proper registration for recording. The light from the gaseous discharge tube will transilluminate the character, and such character will be recorded on a photographic film as will be subsequently explained. Since the drum hubs 60 are hollow, it is possible to provide supports extending from the outside of the drum through the hubs and into the interior of the drum to support the discharge tubes therein. A cable may be also led into the interior of the drum through one of the hollow hubs. Such cable affords the leads to provide current to the individual discharge tubes. The terminal ends of the tubes fit into conductive 45 socket elements which are molded in a block of 50 insulating material 70, the block being supported by suitable brackets 72. Insulating separators 74 of opaque material are provided between the tubes to prevent illumination from a tube related 55 to one character column to effect other character columns. It will be understood that a single tube is provided for each column of characters on the drum. A mask 76 with a central slot 78 is interposed between the drum and a camera unit of the recording section so that only a single line of characters will be photographed at one time.

Reference to Figs. 6 and 7 will illustrate the nature of the camera unit including the means for supporting film spools and for feeding film 65 past a lens. A camera housing 80 is adapted to fit into flanges 82 attached to one end of the section housing 12. The camera housing may be removably held in position by means of thumb nuts 84. A camera frame plate 86 has mounted 70 therein three rotatable shafts 88, 90 and 92, the shafts having fixed thereon film feed sprockets 94, 96 and 98, respectively. These sprockets are adapted to fit a color sensitive film strip 100 which is provided with the usual sprocket holes at the longitudinal marginal edges thereof. A

film take-up spool 102 is provided for the film, this spool being mounted on a rotatable shaft 104. Film feed is effected from a film spool 106 mounted for rotation on a spool shaft 108 upon energization and successive deenergization of a film feed solenoid 110 (see Fig. 6). Energization of the solenoid lowers a linkage system 112 which carries a feed pawl 114, the feed pawl 114 being engaged with a ratchet wheel 116 which is fixed to a pinion 118. The ratchet wheel 116 and the pinion 118 are rotatably mounted on a stud shaft 120. The pinion 118 meshes with a gear 122 which has attached to it a smaller gear 124. The gear 124 in turn meshes with a gear 126 which is fixed to the shaft 90 from which the sprocket 96 is driven. Gearing 128 also transmits motion to the upper sprocket shaft 88. Gearing 130 also drives the lower sprocket shaft 92. The lower sprocket shaft 92 carries a pulley 132, which through a belt 134 drives a pulley 136 fixed to the take-up spool shaft 104. Energization of the solenoid 110 lowers the linkage system 112 and the pawl 114 carried thereby. Upon deenergization of the solenoid 110, a spring 138 restores the linkage and pawl to normal position. During the restoring motion of the pawl, it advances the ratchet wheel 116 one step. Each advancing step of the ratchet wheel through the drive connections previously described drives the various sprocket wheels and the take-up spool and advances the film one line space. A spring pressed lever 140 (Fig. 7) rests in contact with the film on the supply spool 96, and when the film on the supply spool is substantially exhausted, the lever 140 will swing to a position in which contacts 142 are permitted to open. In a manner which will be subsequently explained, the opening of contacts 142 terminates the machine operation.

As best seen in Fig. 6 of the drawings, a housing plate member 144 provides support for a lens and shutter assembly 146. The shutter assembly includes a shutter operating member 148. The shutter is adjusted for a so-called bulb exposure operation, the same being normally open during recording. The shutter is opened by moving the shutter operating member 148 upwardly, and the shutter is closed upon return of the operating member 148 to its lower position as viewed in Fig. 6. The member 148 abuts the top of a slide 150 having a pin and slot connection with a lever 152. The lever 152 is pivoted on a stud 154, and an extension of the lever 152 beyond its pivot point rests in contact with a detent 156. With the parts in position as shown in Fig. 6, the lever 152 is at its counterclockwise limit of movement, and the connecting slide 150 is in its upper position in which it holds the shutter operating member 148 in shutter opening position. In the other position of the parts, the lever 152 is in clockwise displaced position, and the operating slide 150 is in its lower position in which it permits the shutter operating element 148 to move the shutter to closed position. The detent 156 is spring-actuated and contacts with the end of the lever 152 to maintain the lever in either of its two positions. Operation of the shutter accordingly may be effected by rotation of the lever 152 about its pivot.

Circuit diagram

Before the machine is placed into operation to record a run of cards, certain plug connections must first be made. Assuming that auto-control is desired on several classification columns, plug

connections for those columns must be made from the plug sockets 158 of the advance sensing brushes B-1 to the sockets 160 which are connected to the pick-up coils p of the usual duo wound auto-control relays PH. Other plug connections are made from sockets 162 of these same pick-up coils to the double sockets 164 which are wired to the regular sensing brushes B-2 for the classification columns. If two columns, for example, are to be used for auto-control, two pick-up coils of relays PH are plugged up in this manner and plug connections also are made from a pair of the 166 sockets to the 168 sockets which are wired to contacts PH-2 of the two utilized PH relays. The number of connections between 166 and 168 will correspond to the number of columns which are plugged up for auto-control.

Other plug connections are made from desired ones of the sockets 164 of the B-2 brushes to sockets 170 which connect to relay coils E. It will be understood that one relay coil E is provided for each column of recording, but for simplicity in the circuit diagram only three of such coils are shown. The circuits completed through coils E are the sensing circuits established through card perforations, and they control the recording of designated characters. The current supply for these sensing circuits is at relatively low line voltage. On the other hand, with the present machine, the gaseous tubes by which the film is exposed are fired with current at a relatively high voltage, and it is desirable that the high voltage circuits be isolated from the sensing circuits. Accordingly, the relay coils E are utilized, these being energized under line voltage applied through the card sensing circuits. These relays E in turn are utilized to connect up the gaseous tubes to receive high voltage current and to be fired for recording as will be subsequently explained.

The opposite terminals of each individual gaseous tube 68 are connected to plug sockets 172 and 174. A plug connection is made from the 174 socket of a tube to a 176 socket and another plug connection is made from the 172 socket of the tube to a 178 socket. It will be understood that as many tubes are utilized as are necessary for the required number of columns to be recorded. In practice there is one tube for each column of characters upon the drum and while only a few tubes have been shown in the circuit diagram for simplicity of illustration, it will be appreciated that any number may be provided. Other plug connections are made from plug sockets 180 to plug sockets 182. The latter plug connections are in the charging circuits of certain condensers commonly designated K.

It may here be mentioned that with the present machine exposure of variable data from the character carrying drum 62 is effected by flashing the tubes at the proper differential time. Such tubes required considerable voltage to flash or fire them. In order to provide such voltage, according to the present invention, use is made of sets of condensers K, one set of condensers being provided for each tube in the system. In general, it may be stated that the condensers are charged from the relatively low voltage D. C. supply line with the condensers of each set connected in parallel. Accordingly, each condenser of the set will be charged to approximately the line potential of the D. C. supply line. After the condensers are thus charged and before recording, provision is made for reconnecting the con-

densers of each set in a series relation. With the condensers connected serially a high potential is available for flashing or firing the related tube.

It will be further appreciated that if a tube associated with a drum column should fail to fire for any recording operation, the result would be that there would be failure of film exposure for that particular column. Unless means is provided for the immediate detection of tube failure, many lines of improperly exposed film might be run through the machine before final examination of a developed film would make it apparent that one or more tubes had failed to fire as intended. To prevent such undesired operation, testing and indicating means are provided. While this testing and indicating means will be subsequently described in greater detail, its general principle of operation may be mentioned here. If a particular tube fails to fire during a cycle, its related bank of firing condensers will retain a charge after the recording period of the cycle. This retained charge is utilized to energize a testing relay. If such a testing relay becomes energized, an indicating lamp pertaining to the particular column of undischarged condensers is illuminated and further the machine operation is automatically terminated. On the other hand, if a set of condensers after recording operations retains no charge, the testing relays will not be energized, the indicating lamp or lamps will not be illuminated and the machine operation will be permitted to continue.

Assuming the proper perforated records are in the supply magazine 36 (Fig. 1), the operator of the machine first closes the main line supply switch 184 (Fig. 8) providing D. C. current supply to buses 186 and 188. The start key is now depressed, closing start key contacts 198 to complete the following circuit: from the line 186, through the serially connected D-1 contacts of the various detecting and testing relays D, through the master auto-control contacts G-1, through the start key contacts 198, through the film lever contacts 142 and through the card feed clutch magnet 39 to the other side of the line 188. A branch circuit is also completed through a holding relay H which on energization closes contacts H-1. Energization of the magnet 39 starts card feeding in the customary manner and the cards are advanced from the supply hopper. In the first machine cycle a card reaches a position in which its leading edge is under the brushes B-1 in which position the card lever contacts 46a are closed. Closure of these card lever contacts causes energization of the relay coil M, closing contacts M-2 to provide a holding circuit for the coil through cam contacts CF-1. Coil M also closes contacts M-1. Contacts M-1, the stop key contacts, and now closed contacts H-1, shunt the start key contacts 198 so that the start key may now be released and the machine will continue in automatic operation until the card supply is exhausted or a change in card group occurs. During the second card cycle, the first card is fed to a position in which it causes the second card lever contacts 43 to close. Accordingly, coil N is energized, closing contacts N-1 which are in shunt with contacts M-1. Coil N also closes contacts N-2 to provide a holding circuit for the coil by way of cam contacts CF-2. The holding circuits for the relay coils M and N are provided so as to maintain the coils energized during the intervals in which the card lever contacts open between successive cards.

During the third card cycle, the first card will

be sensed by the B-2 brushes and the second card will be sensed by the B-1 brushes. At the beginning of the third cycle, a charging circuit is established to the condensers K. With the card lever relay coil N energized, relay contacts N-3 are closed and a circuit is established from the line 186, through N-3, through a commutator timer CD-1 to a line 192, thence through a resistor in parallel through the normally closed switching contacts R-2 and the various K condensers of the set, thence out through the normally closed S-2 switching contacts to a line leading to the plug sockets 180, thence via the plug connection to 182 to the line 188. Provision is made for reconnecting the condensers from their parallel charging relation to a series discharging relation. Closure of cam contacts CF-6 at the time shown in the timing diagram establishes an energizing circuit for relays R and S. With the relays R and S energized, the contacts R-2 and S-2 open and the contacts R-1 and S-1 close. With the latter contacts closed, the several condensers K of each set are connected in series relation.

It may be here mentioned that there is a CD-1 timing commutator for each of the sets of condensers and all of the sets which have been connected to the line 188 through plug connections between sockets 180 and 182 are concurrently charged.

During the third machine cycle, the leading card is sensed, the recording control magnets E are energized, and the auto-control circuits are set up. Assuming that the cards under the brushes have agreeing group designating perforations, the auto-control circuits are established as follows: from the line 186, through the M-3 relay contacts, cam contacts CF-9 to common brush and contact roll 42, thence through the B-1 brushes which sense the group perforations, thence through the plug connections between sockets 158 and 160, through the pick-up coils p of the auto-control relays PH, thence through the plug connections from 162 to 164, back through the B-2 brushes to the contact roll 44, through CF-7 cam contacts, through relay contacts N-4 and back to the line 188. The auto-control magnets PH are of the usual dual winding type and the energized pick-up coils close the holding contacts PH-1 to energize the companion holding coils h through circuits extending from the line 186 and through the cam contacts CF-4. The energized PH magnets open the related PH-2 contacts so as to prevent energization of the master auto-control relay coil G. It may be pointed out that if the cards do not have corresponding group perforations, then the PH-2 contacts will remain closed and upon closure of the cam contacts CF-8 near the end of the cycle, the circuit of coil G will be established via relay contacts N-5. Coil G will then open contacts G-1 to break the card feed clutch magnet circuit.

The relay coils E are energized under the control of the B-2 brushes as they sense the character designating perforations in the card in columns where recording is desired. The circuits are from line 188, through the N-4 contacts now closed, the CF-7 contacts to contact roll 44, thence through B-2 brushes, through the plug connections from 164 to 170, through the relay coils E and back to the line 186. It will be understood that the relays E are energized at differential times in accordance with the differential positions of the holes in the record cards. Relay coils E only energize momentarily but upon ener-

gization, they close their related E-1 contacts. With such E-1 contacts closed, a tube flashing circuit or circuits are established as will now be described.

These circuits extend from the right hand terminal of the lowest K condenser of a set, for example the left hand set in Fig. 8, through the condenser, thence through the wire which extends to the second S-1 contacts from the bottom of the now closed S-1 contacts, then through the next condenser and so on in succession in series through the various condensers and the S-1 contacts, finally through the uppermost condenser, through the now closed R-1 contacts, through the plug connection between plug sockets 176, 174, thence through the tube 68 or 68A, depending on the position of the CCM-2 contact, through the plug connections between sockets 172 and 178 via downwardly extending wire, through the now closed E-1 contacts, through a timing commutator CD-2, via wires 194, back through a resistor 196, through the lowest S-1 contact and back to the starting point. It will be understood from the foregoing that the condensers discharge through the related tube when the condensers are connected in series relation.

It may be here mentioned that the commutator CD-2 is timed for a very short duration of circuit closure, which duration is sufficient to fire the tube and thereby effectively exposing the film by transilluminating the passing character of a character column on the drum.

It will be understood that while the circuit has been traced for one particular column of condensers and for one tube, exposures may occur for a multiplicity of columns.

The selected character on the drum passes the exposure position at the time the related tube is illuminated under control of the corresponding index point in the card, the commutator contacts CD-2 closing for a short period of time during which the particular index point is being sensed. The drum characters selected by the designations in the card columns can thus be exposed and recorded at differential points of the cycle and such exposure for different columns may occur either concurrently or at different times depending on whether like or unlike designations are sensed in the card columns. Exposure of characters in different columns during a card cycle will be effected on a common line on the film.

Feed of the film will follow each exposure. Upon closure of cam contacts CF-3 a circuit is completed from the line 188, through relay contacts N-6 now energized, through the CF-3 contacts and through film feed solenoid 110 (see Fig. 6). Energization of the solenoid followed by its subsequent deenergization upon opening of cam contacts CF-3 causes line spacing of the film in the manner previously described.

Provision is now made for detecting mis-operation of the tube or tubes. If a tube has failed to fire there will be a charge remaining in the condenser bank associated with the particular tube which failed to fire. Before testing is effected, relays R and S are deenergized by opening of cam contacts CF-6. Accordingly, R-2 and S-2 contacts reassume the normal relation shown in the wiring diagram. Assuming a charge remaining in one or more of the condensers K, current will flow from the charged condensers through the R-2 contacts now closed, to a line 198, thence through relay contacts N-7 now closed, through cam contacts CF-5, which close

at the time shown in the timing diagram, through one of the detecting relay coils D, through a resistor 200, through the S-2 contacts to the opposite sides of the charged condenser. The current in the circuit thus established is sufficient to energize the D coil, closing related contacts D-2 to establish a circuit through key contacts 202, through an indicating lamp 204, through the D-2 contacts, through the D relay coil, through resistor 200, through a plug connection from 180 to 192 and back to line 188. A lamp 204 is provided for each condenser column (see also Fig. 1). Failure of any plugged in lamp may be detected at once by noting whether its associated signal lamp 204 has been illuminated. The energization of relay D also opens its related D-1 contact and the opening of such D-1 contact interrupts the holding circuit to the card feed clutch magnet 30, thus causing deenergization of the card feed clutch magnet and stopping further feed of cards through the card handling section of the machine. After there has been a tube failure, the operator detects which tube is faulty and replaces it. Thereafter the warning circuit through lamp 204 and related coil D is opened. Opening up of such circuit for relay D and the signal lamp 204 is afforded by manual operation of the key which controls normally closed key contacts 202.

With the present machine, when a change in control occurs between card groups, provision is made for effecting additional film feed to give distinct spacing between the successive groups. When successive cards with disagreeing group control perforations traverse brushes B-1 and B-2, one or more of the auto-control magnets PH are not energized and the related PH-2 contacts remain closed, and when the CF-8 contacts close, coil G is energized as explained before, through the closed PH-2 contacts and the N-5 contacts. Coil G closes holding contacts G-2 providing a holding circuit for the coil, through cam contacts C-1. Energization of coil G also opens contacts G-1 to break the card feed clutch magnet circuit, causing interruption in card feed. Coil G also closes contacts G-3, establishing a circuit from line 188, through these contacts, through cam contacts C-2 when closed, then through the film feed magnet 110 to the line 186. Upon opening of the cam contacts C-2, the circuit just traced is broken and the magnet 110 deenergized. As a result the film is line-spaced. Coil G is still energized and contacts G-3 still closed when cam contacts C-3 close. Contacts C-3 function to the same effect as contacts C-2. Hence a second energization and deenergization of magnet 110 occurs, causing a second line spacing of the film. Following this additional line spacing operation, provision is made for automatically reinitiating card feed. Reinitiation of card feed is effected as follows: With relay contacts G-4 now closed, the closure of cam contacts C-4 completes a circuit from line 186, through G-4, and C-4, to the card feed clutch magnet 30 and coil H. Card feed of records pertaining to a following group will now automatically be resumed.

Color screen operation

As hereinabove indicated the present invention is designed for the photographic recording of data in selected color, and several forms of mechanism for such color recording have been disclosed herein. In the description to follow immediately hereinbelow, one form of the inven-

tion which involves the use of shiftable color screens will be described, and for the purpose of this description reference may be had to Figs. 2 through 5, inclusive. In these figures the character drum 62 hereinabove mentioned is the principal film exposing medium. Disposed immediately in front of the drum 62 are a series of strips 206 which are preferably formed of thin metal, and which are so arranged that a strip is directly in alignment with a character column on the drum. The strips 206 are provided with two cut-out portions 208 and 210. The cut-out portion 210 has attached thereto a translucent color screen 212. The color screen 212 may be secured to the strip 206 by means of an adhesive cement. The cut-out portion 208 ordinarily has no color filter overlying the same since it constitutes the aperture used during normal recording operations.

The strips 206 pass through two sets of horizontal guides 214 and 216, and a further set of restoring guides 218, which cooperate with a projecting stud 220 carried by each strip for the purpose of restoring the color screen strips as will appear more fully hereinafter. Springs 222 and 224 are secured to the upper and lower extremities respectively of the strips 206. The opposite end of the spring 222 is secured to an upper cross bar 223, and the opposite end of the spring 224 is secured to a lower cross bar 225. The spring 224 is stronger than the spring 222 and serves to pull the strip downwardly upon release of the strip so that the color screen 212 is in registration with a character of the drum 62 which is in recording position. The spring 222 is merely strong enough to hold the strip 206 in upright position and to provide a flexible connection between the upper end of the strip and the supporting cross bar 223.

Normally the strips 206 are in the position shown in Figs. 2 and 4 of the drawings, and they are held in this position by the latching action between a projection 230 formed in the face of the strip and an electromagnetically operated latch 232. With the strip in the position shown, the cut-out portion 208 is aligned with exposure slot 78 in a light mask 78a. Accordingly, when a flash tube such as the tube 68 is illuminated for recording purposes, the recording on the film, in this case color film, will be a bluish white if the lamp 68 is a mercury vapor lamp, or the recording will be red if the lamp is a neon tube. For the purpose of illustration, let it be assumed that the lamps 68 are of the mercury vapor type.

The latches 232 are individual for each strip 206, and each latch is controlled by a related electromagnet 234. The latches are provided with pull rods 236 which connect them with their magnets. When it is desired to change from the bluish white recording to the red recording in any particular column or columns, the corresponding magnet or magnets 234 are energized, thereby shifting their associate latches 232 out of engagement with the related strip projections 230. This will permit the spring 224 to move a released strip 206 downwardly until its stop studs 220 engage the restoring guide 218. Color filter 212 will then be in alignment with the exposure slot 78. When the related tube 68 is flashed, the recording will be in red rather than in the bluish white color in which the recording appears when the exposure is through the cut-out 208.

The driving action of the restoring guides 218 may now be described with reference to Figs. 2 and 3 of the drawings. A cam 238 is secured to

the gear 56 which engages the drive gear 58 for the character drum. A follower link 240 constitutes a connection between the cam 238 and a sliding cross-head 242 which slides on vertical bars 244. A similar structure is provided at both sides of the machine so that the restoring guide 218 has imparted thereto an even movement. A shaft 246 extends through the side plates of the unit to provide a drive for the opposite restoring cam. A slot 245 is cut in each side of the frame to permit connection between the cross-heads 242 and the restoring guides 218, as well as for the purpose of providing for the vertical reciprocation of the latter. The contour of the cams 238 is such that they start their upward movement at approximately 11 in the cycle and return to rest position as shown in Fig. 3 of the drawings shortly before 9 in the cycle.

The circuit controlling the normal recording of data has been described hereinbefore, and it is therefore appropriate at this point to further describe that part of the control system which governs the position of the color strips 206. The circuit connections necessary to effect control of the magnets 234 therefore follows. Reference to Fig. 9 of the drawing will disclose the additional control circuits that must be imposed on the general control circuit shown in Fig. 8 of the drawing for the control of the hereunto described color recording system.

Control for the color control magnets 234 will be under the influence of a hole in the record card being analyzed, for example, a hole in the X position, such as the card in G. F. Daley et al. Patent No. 1,954,041. One hole in the position of a column may control the color of the recording in that column only, or an X position hole may control the color control magnets 234 in a plurality of columns. Assume, for example, that an X hole is sensed in the 15th column of the record card. Referring to Figs. 8 and 9, a plug hub 248 is connected by a plug wire to the upper brush plug hub 158 of Fig. 8 for the 15 column. This connection is indicated by the dotted line in Fig. 9 of the drawings. Assuming that it is desired to record the first three numbers on the left in red every time a perforated card appears, a plug connection is made from the plug hub 250 to the plug hub 252-1, and from the plug hub 252-1 to plug hub 252-2, and finally from the plug hub 252-2 to the plug hub 252-3. The suffix 1, 2 and 3 attached to the plug hub numeral 252 indicates the first, second and third column from the left of the recording. In this example the first, second and third columns might contain a customer's balance, and the punched record cards may represent debit cards against that customer's account. In the event it is desired to record in red color in only one column, the plug connection would obviously be made only from plug hub 250 to the plug hub 252 for the single column in which the red color recording under X control is desired. In the event that it is desired to record different columns in red for one card than the columns it is desired to record in red for another card, more than one X control will be plugged up in a manner similar to that just described.

With the plugging as described, whereby the control circuit of Fig. 8 is modified by the imposition of the additional controls of Fig. 9 and with cards disposed in the hopper 36, the main switch 184 may be closed and the start key may be depressed, thereby setting the card handling and sensing unit 10 into operation, and as a con-

sequence the recording unit 12 which is under its control. When a card bearing an X perforation is sensed, a circuit is completed from the line 186, through relay contacts M-3, through cam contacts CF-9, through the common brush and contact roll 42, through the hole in a card being sensed, and through the reading brush B-1 to the exit plug hub 158. The circuit further extends from the plug hub 158 to the plug hub 248 (Fig. 9) to energize the Y pick-up magnet, and from thence to the other side of the line 188. Relay Y, when energized, closes its contacts Y-1, which maintain the relay energized by a circuit through CF-4, to the other side of the line. Shortly thereafter relay contacts CF-10 close to complete a circuit from the line 186, through contacts CF-10, through relay contacts Y-2, through relay Z, and to the other side of the line 188. The relay Z is maintained energized into the following cycle for controlling purposes through its contacts Z-1, and cam contacts CF-11. At the start of the cycle in which color control is desired, a circuit is completed from the line 186, through the cam contact CF-12, through relay contacts Z-2, now closed, plug hub 250 and to one or more of the plug sockets 252, and consequently to one or more of the color strip control magnets 234, and thence to the other side of the line 188.

Energization of a magnet 234 will trip the latch 232 as previously described, thereby permitting the color screen 212 to drop into alignment with the exposure slot 78. Accordingly, when the tube 68 is flashed, the recording will be effected in a different color than would occur during regular operations of the machine when the color screen 212 is not moved into alignment with the exposure slot.

Near the end of the cycle the color screen strips 206 which have been released and lowered under the influence of their respective springs 224 will be restored to their upper latched position under the action of the restoring guides 218. The manner in which recording of more than one color may be effected under X control with a colored mask or color filter has just been described.

Multiple character drum operation

The foregoing manner of selectively reproducing data in color on photographic film is one way of achieving the general objective of the present invention, but in order to indicate the scope of the invention herein a further method for accomplishing the purpose under perforated card control will be described specifically, and this description will proceed mainly with reference to Figs. 6 and 7 of the drawing, insofar as mechanical aspects are concerned and with reference to Figs. 8 and 10 of the drawings, insofar as automatic control of the mechanism may be concerned.

In accordance with the modified recording structure there are provided two character drums and two sets of gaseous discharge tubes, the tubes being so selected that the illumination from the tube itself results in a color of the desired character. Circuit controls to permit the flashing of tubes in one or the other of a pair of drums being equipped with tubes of different illuminating characteristics are provided, and an optical system which permits recording from two drums to a common film is part of the structure as shown in Fig. 7. In addition to the character drum 62, there is provided in the modified form of the invention a second identical character drum 254. Each drum is provided

with a drum driving gear, and particularly the drum 254 has associated therewith a driving gear 256. In order to impart motion to the drum 254, a set of idler gears 258 interconnect the gear 256 with the gear 58 which drives the drum 62. Idler gears 258 provides drive from the gear 58 to the gear 256, and accordingly the drum 254 will rotate synchronously with the drum 62 and in the same direction.

The path of light when a tube in a drum is flashed may best be traced with reference to Fig. 7 of the drawing. The light from the drum 254 will impinge on a mirror 260 and will be reflected to a semi-reflecting and transmitting prism 262 of the type shown and described in the U. S. Patent No. 2,371,120 to R. T. Blakely. The light is then reflected to the lens 146 of the camera assembly and a character image will be recorded on the film. Light from the drum 62 will impinge on a mirror 264, and it will be reflected to a mirror 266 which in turn passes the light through the prism 262 and through the camera lens 146 to the film. The gaseous tubes 68A in the drum 254 may contain mercury vapor and the gaseous tubes 68 of the drum 62, in this instance, may contain neon. It has heretofore been explained that the film exposed to the rays of a mercury vapor lamp will produce a bluish white image, whereas the same film exposed to the rays of a neon lamp will result in a red recording. Consequently, there is no necessity in the modified form of the mechanism for the interposition of color screens, inasmuch as the light sources themselves determine the color in which the character will be recorded on the film.

The circuit connections for controlling the modified form of the invention will be understood by reference to the general control diagram of Fig. 8 when viewed in connection with the specific control diagram of Fig. 10 which is imposed on the general control system for the selective illumination of lamps in either character drums 62 or 254. The tubes 68 and 68A are connected as shown and as will be explained; the selection of one of these is effected by relay contacts CCM-2 (Fig. 8).

For control of the lamps under the influence of an X hole of a record card, it will be necessary that a plug hub 268 (Fig. 10) be connected by a plug wire to the upper brush plug hub 158 of Fig. 8, this connection being made, for example, at the 15th column position. The plug wire is shown in dotted lines in Fig. 10. Assuming that it is desired to record the first three numbers on the left in red every time an X perforated card appears, a plug connection is made from the plug hub 270, to the plug hub 272-1, and from the plug hub 272-1 to the plug hub 272-2, and from the plug hub 272-2 to the plug hub 272-3, the suffix 1, 2 and 3 used in connection with the plug hub numeral 272 indicating the first, second and third column from the left of the recording. In this example the first, second and third columns again might contain a customer's balance, and the X punched cards may represent debit records for charge against the customer's account. In the event it is desired to record in red color in only one column, the plug connection would obviously be made only from plug hub 270 to one of the 272 plug hubs, and in this case for the particular single column which is to be recorded in red under X control. In the event it is desired to record different columns in red for one card than

the columns it is desired to record in red for another card, more than one X control will be plugged up in a manner similar to that just described. The plug connections from sockets 172 to 178 and from 174 to 176 are as previously described. With the card hopper 36 supplied with cards and the machine set in operation by closure of the line switch 184 and depression of the start key 190, cards will be fed through the card handling and sensing unit 10 as hereinbefore described. When a card bearing an X perforation is sensed, a circuit is completed from the line 186, through relay contacts M-3, through cam contact CF-9, through the common brush and contact roll 42, through the hole in the card, through the sensing brush B-1, and to the plug hub 158. The circuit further extends from the plug hub 158 to the plug hub 268 (Fig. 10) to energize the pick-up magnet 274, and to the other side of the line 188. Relay 274, when energized, closes its contacts 274A which maintain the relay energized by a circuit through CF-4 to the other side of the line. Shortly thereafter cam contacts CF-10-A close to complete a circuit from the left side of the line 186, through the cam contact CF-10-A, through the relay contacts 274B, through the plug hub 270, the plug wire to the plug hub 272-1, through the relay CCM, and to the right side of the line 188. The relays CCM for columns 2 and 3 will also be energized at this time because of the plug connections from 272-1 to 272-2, and from 272-2 to 272-3. The relays CCM are maintained energized into the next cycle for controlling purposes through contacts CCM-1 and cam contacts CF-11-A.

Accordingly, during the cycle that color control is desired, relay contacts CCM-2 will be shifted so that the gaseous discharge tube 68 containing neon gas will be connected in circuit for illumination during this cycle, rather than the gaseous discharge tube 68A which contains mercury, and the recording will be in red rather than in bluish white.

As an alternative to having tubes with different gases, similar tubes such as those containing mercury or neon may be used in both of the character drums 62 and 254, but in this instance one drum would have merely cut out characters at the character columns thereon, whereas the other drum would have its characters covered by a transparent or translucent color screen. The circuit controls would be just as described, but the color of the recording would be due to the drum characteristic in the one case and to the lamp characteristic in the other.

It has been previously mentioned in connection with the objects of the invention that a preset color control may be effected for both embodiments of the invention. Considering now the first described embodiment of the invention, and assuming that it is desired as previously described to record in red color in the three left hand columns of the record film, the plug connections from plug hubs 158 to plug hubs 248, and from plug hubs 250 to plug hubs 250-1, etc. are not made. On the other hand, a plug connection is made from a plug hub 158A to plug hub 252-1, and from plug hub 252-1 to a plug hub 252-2, and from plug hub 252-2 to plug hub 252-3. Then the color control magnets 234 of the selected columns will be energized every cycle by a circuit from line 186 through cam contact CF-12, through plug hub 158, and by way of plug connections to the plug hub 252-1, thence to plug

hub 252-2 and to plug hub 252-3, to the magnets 234 and to the other side of the line 186. If only a single column of red recording is desired, it is obvious that only one of the plug hubs 252-1 etc. will be plugged to a 158A plug hub.

In connection with the modified form of the invention, if it is desired to preset color control, the connection from the plug hub 158 to the plug hub 268 is eliminated, and instead of plugging from the plug hub 270 to the plug hub 272-1, a connection is made from plug hubs 276 to selected ones of the plug hubs 272-1, etc., thereby effecting an energization of the selected CCM magnets at every cycle to control the color in the particular column or columns so selected.

As the last cards pass through the sensing section, irrespective of the type of control employed, there is, in effect a break in auto-control, causing stoppage in machine operation. This break in control is due to the fact that relay contacts M-3 are now open and no circuit is provided to the contact roll 42.

What is claimed is:

1. In a machine for the photographic reproduction of records in different colors, a record reading device for reading character designations and color selection indicia in a statistical record, a character member having transilluminatable characters thereon corresponding to character designations on a record to be reproduced, a character transilluminating station, means controlled by said reading device for moving the characters on said member through said station, means under control of a character designation in a record in said record reading device for transilluminating a character at said station, a color sensitive film, means controlled by a record in said reading device for advancing said film through an exposure station, means associated with said character transilluminating station for producing a light beam whose rays are of a predominantly different wave length than those of said first named transilluminating means, and means under control of a color selection indicia of a record in said reading device for selecting said light beam producing means to expose said film at said exposure station to character transilluminating rays produced by said light beam producing means, thereby producing in said film a record reproduction in different colors.

2. In a machine for the photographic reproduction of records in different colors, a record reading device for reading character designations and color selection indicia in a statistical record, a plurality of character member columns having transilluminatable characters thereon corresponding to character designations on a record to be reproduced, a character transilluminating station, means controlled by said reading device for moving the characters on said member through said station, means common to each of said character columns for transilluminating a character at said station, means under control of a character designation in a record in said record reading device for controlling said transilluminating means, a color sensitive film, means controlled by a record in said reading device for advancing said film through an exposure station, means associated with said character transilluminating station for producing a light beam whose rays are of a predominantly different wave length than those of said first named transilluminating means, and means under control of a character designation in a record in said reading device for selecting said light beam produc-

ing means to expose said film at said exposure station to character transilluminating rays produced by said light beam producing means, thereby producing in said film a record reproduction in different colors.

3. In a machine for the photographic reproduction of records in color, a record reading device for reading character designations and color selection indicia in a statistical record, a character member having transilluminatable characters thereon corresponding to character designations on a record to be reproduced, a light source for transilluminating said characters, a character transilluminating station, means controlled by said reading device for moving the characters on said member through said station, means under control of a character designation in a record in said record reading device for energizing said light source to transilluminate a character at said station, a color sensitive film, means controlled by a record in said reading device for advancing said film through an exposure station, a color screen adapted to pass light of a selected wave length that is predominantly different than the wave length of the character transilluminating light rays between said character member and said film, a latch device for holding said color screen in inoperative position, and electromagnetic means under control of a color selection indicia in a record in said reading station for releasing said latch device for selectively moving said color screen into the character illuminating rays, thereby producing in said film a record reproduction in selected color.

4. In a machine for the photographic reproduction of records in color, a record reading device for reading character designations and color selection indicia in a statistical record, a character member having transilluminatable characters thereon corresponding to character designations on a record to be reproduced, a character transilluminating station, means controlled by said reading device for moving the characters on said member through said station, a light source for transilluminating said characters, means under control of a character designation in a record in said record reading device for energizing said light source to transilluminate a character at said station, a color sensitive film, means controlled by a record in said reading device for advancing said film through an exposure station, a color screen adapted to pass light of a selected wave length that is predominantly different than the wave length of the character transilluminating light rays between said character member and said film, means for normally latching said color screen out of the character transilluminating rays, spring means tending to move said color screen into the character transilluminating rays, and electromagnetic means under control of a color indicia in a record in said record reading station for selectively releasing said latching means to permit said color screen to move into the character illuminating rays under the influence of said spring means, thereby producing in said film a record reproduction in selected color.

5. In a machine for the photographic reproduction of records in color, a record reading device for reading character designations and color selection indicia in a statistical record, a plurality of spaced, synchronized character members having transilluminatable characters thereon corresponding to character designations on a record to be reproduced, means controlled by

said reading device for moving the characters on said members synchronously through a transilluminating position, a separate light source for each of said members, each of said light sources being adapted to produce a beam of light whose rays are of a predominantly different wave length than those of each other light source, a color sensitive film, means controlled by a record in said reading device for advancing said film through an exposure station, and means under control of a designation in a record in said record reading device for selectively energizing said light sources to expose said film at said exposure station to the transilluminating rays through the selected one of said character members.

6. In a machine for the photographic reproduction of records in color, a record reading device for reading character designations and color selection indicia in a statistical record, a plurality of spaced, synchronized character members having transilluminatable characters thereon corresponding to character designations on a record to be reproduced, means controlled by said reading device for moving the characters on said members synchronously through a transilluminating position, a separate light source for each of said members, each of said light sources being adapted to produce a beam of light whose rays are of a predominantly different wave length than those of each other light source, a color sensitive film, means controlled by a record in said reading device for advancing said film through an exposure station, and means under control of a color selection indicia in a record in said record reading device for selectively energizing said light source to expose said film at said exposure station to the transilluminating rays through the selected one of said character members.

7. In a machine for the photographic reproduction of records, a record reading device for reading character designations and color selection indicia in a statistical record, a plurality of spaced, rotary character drums having transilluminatable characters thereon corresponding to character designations on a record to be reproduced, means controlled by said reading device for moving the characters on said drums synchronously through a transilluminating position, a separate lamp for each of said drums, each of said lamps being adapted to produce a beam of light whose rays are of a predominantly different wave length than those of each other lamp, a light sensitive film, means controlled by a record in said reading device for advancing said film through an exposure station, and means under control of a color selection indicia in a record in said record reading device for selectively illuminating said lamps to expose said film at said exposure station to the transilluminating rays through characters in the selected one of said drums.

8. In a machine for the photographic reproduction of records in color, a record reading device for reading character designations and color selection indicia in a statistical record, a plurality of spaced, rotary character drums having transilluminatable characters thereon corresponding to character designations on a record to be reproduced, means controlled by said reading device for moving the characters on said drums synchronously through a transilluminating position, a neon lamp in one of said drums, a mercury vapor lamp in the other of said drums,

a color sensitive film, means controlled by a record in said reading device for advancing said film through an exposure station, and means under control of a color selection indicia in a record in said record reading device for selectively illuminating either of said lamps to expose said film at said exposure station to the transilluminating rays through characters in either of said drums.

9. In a machine for the photographic reproduction of records, a record reading device for reading character designations and color selection indicia in a statistical record, a pair of spaced, rotary character drums having transilluminatable characters thereon corresponding to character designations on a record to be reproduced, means controlled by said reading device for moving the characters on said drums synchronously through a transilluminating position, separate lamps for each of said drums, each of said lamps being adapted to produce a beam of light whose rays are of a predominantly different wave length than those of each other lamp, a color sensitive film, means controlled by a record in said reading device for advancing said film through an exposure station, and means under control of a color selection indicia in a record in said reading device for selectively illuminating either of said lamps to expose said film at said exposure station to the transilluminating rays through characters in either of said drums.

10. In a machine for the photographic reproduction of records in color, a record reading device for reading character designations and color selection indicia in a statistical record, a 35 plurality of spaced, rotary character drums hav-

ing transilluminatable characters thereon corresponding to character designations on a record to be reproduced, means controlled by said reading device for moving the characters on said drums synchronously through a transilluminating position, a lamp in one of said drums, a lamp generating light rays of a predominantly different wave length than those of said first named lamp in the other of said drums, a color sensitive film, means controlled by a record in said reading device for advancing said film through an exposure station, and means under control of a color selection indicia in a record in said record reading device for selectively illuminating said lamps to expose said film at said exposure station to the transilluminating rays through the characters of the selected one of said drums.
